UNITED STATES PATENT OFFICE.

FRED W. BILLIG, OF JACKSON, MICHIGAN, ASSIGNOR TO THE SPARKS-WITHINGTON COMPANY, OF JACKSON, MICHIGAN, A CORPORATION OF OHIO.

SIGNALING DEVICE.

Application filed June 18, 1925. Serial No. 37,458.

This invention relates to a certain new and improved signaling device, and more particularly to a signaling device or horn of the magnetically-actuated type.

5 The main object of the invention is the production of an efficient signaling device of substantial construction, and of economic manufacture and arrangement, and which will produce a signal of the desired character, 10 pitch and amplitude.

15 Other objects and advantages relate to the details of the structure and the form, position, arrangement and association of the parts thereof, all as will more fully appear from the following description, taken in connection 20 with the accompanying drawings, in which:—

Figure 1 is an elevation of a horn of this invention.

Figure 2 is a section taken on line 2—2, 25 Figure 1.

The structure of signaling device here illustrated is of the magnetically operated diaphragm type, and as shown, comprises a rear diaphragm case-section —1— having its central portion dished and of substantially cylindrical cup-shape, and formed at its central portion with an opening for the reception of the magnet or magnetic field —2—. The diaphragm —3— is clamped between the rear 30 diaphragm case section, and a ring or washer —6— interposed between the front diaphragm case section —4— and the edge of the diaphragm, bolts —5— being provided for clamping the case sections, the washer and the diaphragm together.

35 The front diaphragm case-section —4— carries a suitable projector 95. The magnet —2— may be secured to the diaphragm case section in any suitable manner not herein necessary to illustrate or describe, and as illustrated, the magnet is formed with a continuous channel or groove —12— which surrounds the central passageway and is adapted to receive a field coil —13—. This field coil lies wholly forward of the rear surface of the magnet —2— in the assembled structure so that the armature —19— in the operation of the structure will contact directly with the rear surface of the magnet —12—.

40 The diaphragm —3— as here illustrated, is provided with a central opening surrounded by a reinforcing internally threaded ring or collar —14— permanently and rigidly secured in any suitable manner to the edge of the diaphragm bordering the central opening.

A sleeve —15— is provided with an externally threaded portion for co-action with the internally threaded collar —14— which constitutes a rigid portion of the diaphragm and one end of the sleeve projects forwardly from the diaphragm and may be flattened upon diametrically opposite sides for the reception of a washer or ring —16— which has a non-circular opening adapted to fit the end of the sleeve —15— so that the ring can be used to 60 rotate the sleeve, and the ring is secured in position upon the end of the sleeve by means of a headed bolt —17— and is clamped against the bushing —14— at the center of the diaphragm, the head of the bolt being preferably 65 separated from the ring —16— by means of washer —18—. Bolt —17— extends entirely through the sleeve —15— and projects from the rear portion thereof, and passes through the armature —19—, washer —20—, leaf 70 spring —21—, and is threaded into the substantially flat base —22— of the yoke —23— which rests upon the outer surface of the spring —21—.

75 For the purpose of effecting a rigid and 80 tight engagement between the diaphragm —3—, disk —16—, sleeve —15—, bolt —17—, armature —19—, washer —20—, spring —21—, and yoke —23—, the rear end of sleeve —15— is somewhat enlarged and 85 spherically shaped so as to seat tightly in a substantially similarly spherically shaped recess in the adjacent side of the armature —19—, and the opposite side of the armature is formed with a flat recess of circular form 90 for the reception of washer —20—.

95 Washer —26— is provided with a substantially spherical seat for contact with the rear curved or spherical portion of the washer —20—, such washer —26— being interposed between the spring —21— and the washer —20— and having recesses for the reception of the lugs —24— formed on the flat base —22— of the yoke —23—, and which lugs extend through similarly shaped recesses in 100 the spring —21—, but do not contact with the rear spherical surface of washer —20—.

105 The main feature of this invention resides in the form and construction of the yoke —23—. This yoke is formed of a single piece of sheet metal, as for instance brass, and has its base —22— formed with a central internally threaded opening for the reception of the rear end of bolt —17— and also with the lugs —24— projecting from the bottom of 110

the base. An upright —80— rises from the base —22— and has an arm —81— bent at substantially right angles so as to lie parallel with but spaced from the base —22— 6 and is formed with an internally threaded opening aligned with the bolt —17—, which opening is adapted to receive an adjustable screw —41— adapted to be locked in any position of adjustment by means of nut —82—. 10 The adjustable screw —41— carried by the yoke —23— acts to operate the make and break mechanism for the circuits of the horn, and to effect this purpose a built-up pedestal is provided at the rear of and carried by the 15 diaphragm case-section —1—, and this pedestal —83— carries the contacts which are intermittently separated and brought together as hereinafter described. This pedestal may consist of a number of separate parts secured 20 together and to the case section by means of one or more bolts —57—, and the pedestal includes a rigid bar —34—, one end of which is mounted upon the bolts —57— and rigidly secured in the pedestal, and the other end of 25 which projects inwardly from the pedestal toward the yoke —23— and carries an adjustable contact member —38—, which is adapted to intermittently contact with a second contact member —37— carried by a spring-arm 30 —32— which in like manner has one of its ends mounted in the pedestal —83—. The bar —34— and the spring-arm —32— are insulated from each other in the pedestal in any suitable and well-known manner. The 35 flexible arm —32— extends beyond the contact —37— and into the space between the base —22— and the overlying arm —81— of the yoke, and is provided at its end with a cup-shape member —39— containing any 40 suitable hard insulating contact material —40— for contact with the adjustable screw —41— carried by the yoke —23—.

It will be obvious that as this yoke —23— moves back and forth with the armature, the 45 adjacent screw will act to separate the contacts —37— and —38—, and then permit their engagement. The yoke 23 as shown, has a rib —84— centrally disposed of the upright —80— and extending upwardly 50 around the bend into the arm —81— to provide the necessary rigidity for this portion of the yoke.

The horn so far described constitutes in 55 itself a useful article of manufacture, but for the purpose of providing improved results of a substantial nature, the bolt —17— is formed with an extension 85 which may be formed with or secured to the bolt in any suitable manner, and for the purpose of illustration, the forward front portion of the bolt —17— is formed with a threaded recess adapted to receive the threaded end of the extension member —85— so that the two

parts are rigidly and firmly secured together and constitute in effect a unitary bolt or rod. 65 The forward end of the extension rod —85— terminates forward of and outside of the projector —8— and is as shown reduced and externally threaded, and extends through the central portion of a spring bar —86— which 70 has its opposite ends rigidly secured to diametrically opposed portions of the forward end of the projector —95—, as for instance, by screws —87— as shown, altho any other suitable means of attachment may be utilized. 75 This spring-bar may as shown be corrugated for the purpose of giving additional strength. Washers 88 and 89 are mounted on the reduced threaded end of bolt 85 upon opposite sides of the spring-bar 86 and a disk 90 is 80 mounted on the rod 85 forward of the washer 89 and is secured in position thereon in any suitable manner, as by nut 91, washer 92 being interposed between the nut and the disk. The disk, or vibratory body 90 is pref- 85 erably of an area slightly less than the area of the forward end of the projector, and is wholly outside the projector, and is preferably formed of bell metal or similar material, and I have discovered that a disk of suitable 90 size and formed of a suitable material when disposed wholly forward of the projector and connected to the armature —19— for direct actuation thereby, produces a new and highly efficient result particularly of the carrying 95 power in the resultant note of the horn.

Obviously the disk 90 may be connected to the armature 19 in various ways for actuation thereby, and may be supported in many and various ways, and altho I have shown and described a specific structure as illustrative of an embodiment of the invention, I do not desire to restrict myself to the details of the structure, as various changes and modifications may be made within the scope of the 105 appended claims.

I claim:

1. A horn comprising a diaphragm, a projector extending forwardly from the diaphragm, a vibratory disk disposed outside 110 the projector, and means for simultaneously vibrating the diaphragm and said vibratory disk.

2. A horn structure comprising a dia- 115 phragm, a projector extending forwardly from the diaphragm, a free edge vibratory member approaching in cross-sectional area the cross-sectional area of the front open end of the projector and disposed outside of and forwardly of the projector, and means con- 120 necting the said vibratory member to the dia- phragm for simultaneous bodily movement therewith.

In witness whereof I have hereunto set my hand this 29th day of May, 1925.

FRED W. BILLIG.
